United States Patent Office

Des. 193,147
Patented July 3, 1962

193,147

GAME DEVICE

Edward G. Brown, 1170 Dover Center Road,
Westlake, Ohio

Filed Nov. 3, 1961, Ser. No. 67,373

Term of patent 3½ years

(Cl. D34—5)

FIG. 1

FIG. 2

FIG. 3

FIG. 4

FIG. 1 is a top plan view of a game device, showing my new design;

FIG. 2 is a side elevation of said game device of FIG. 1, the other side thereof being like the side shown;

FIG. 3 is an end elevation of said game device taken from the left as viewed in FIGS. 1 and 2; and

FIG. 4 is an end elevation of said game device taken from the right as viewed in FIGS. 1 and 2.

I claim:

The ornamental design for a game device, as shown and described.
